Primary Examiner — Susan Bennett Hattan*Assistant Examiner* — Landon Thomas Cassell(57) **CLAIM**

The ornamental design for an electrical connector, as shown and described.

DESCRIPTION

FIG. 1 is a perspective view of an electrical connector;
FIG. 2 is a perspective view thereof;
FIG. 3 is a perspective view thereof;
FIG. 4 is a perspective view thereof;
FIG. 5 is a front view thereof;
FIG. 6 is a rear view thereof;
FIG. 7 is a top view thereof;
FIG. 8 is a bottom view thereof;
FIG. 9 is a right side view thereof; and,
FIG. 10 is a left side view thereof.

The equal length broken lines in the drawings depict portions of the electrical connector that form no part of the claimed design.

1 Claim, 10 Drawing Sheets---
